UNITED STATES PATENT OFFICE.

JOHN G. WHILLDIN, OF PHILADELPHIA, PENNSYLVANIA.

DESIGN FOR A FLOWER-POT.

SPECIFICATION forming part of Design No. 20,133, dated September 2, 1890.

Application filed August 8, 1890. Serial No. 361,470. Term of patent 14 years.

To all whom it may concern:

Be it known that I, JOHN G. WHILLDIN, a citizen of the United States, and a resident of Philadelphia, in the county of Philadelphia and State of Pennsylvania, have invented certain new and useful Designs for Flower-Pots; and I do declare the following to be a full, clear, and exact description of the invention, such as will enable others skilled in the art to 5
10 which it appertains to make and use the same, reference being had to the accompanying drawings, and to the letters of reference marked thereon, which form a part of this specification.

15 Figure 1 of the drawings is a vertical central section. Fig. 2 is a bottom plan view.

This invention has relation to designs for flower-pots; and it consists in the novel form and configuration of parts, as hereinafter set 20 forth.

In the accompanying drawings, the letter A

designates the body portion of the pot, which is of the form of a frustum of a cone, terminating below in the bottom C, having the arc-shaped marginal downwardly-projecting lugs 25 e, separated from each other at their ends by the notches f, as shown.

Having described this invention, what I claim, and desire to secure by Letters Patent, is—

The design for flower-pots, consisting of the conical body portion terminating below in the centrally plane bottom, having the marginal arc-shaped lugs projecting downward and separated at their ends by the notches f, as 35 shown.

In testimony whereof I affix my signature in presence of two witnesses.

JOHN G. WHILLDIN.
